UNITED STATES PATENT OFFICE.

WILLIAM A. MILES, OF SALISBURY, CONNECTICUT.

IMPROVEMENT IN BLAST-FURNACE CHARGING APPARATUS.

Specification forming part of Letters Patent No. 130,652, dated August 20, 1872.

Specification describing a new and Improved Charger for Blast-Furnaces, invented by WILLIAM A. MILES, of Salisbury, in the county of Litchfield and State of Connecticut.

Figure 1 is a vertical central section of my invention. Fig. 2 is a horizontal section of the same.

Similar letters of reference indicate corresponding parts.

This invention relates to a new apparatus for charging all kinds of blast-furnaces with the material to be treated therein, and has for its object to prevent the escape of gases through the charger while feeding the material to the furnace, and also to allow the evening or leveling of the material in the charging vessel.

A in the drawing represents the upper charging vessel or hopper to a blast-furnace of suitable kind. This vessel is made of cylindrical, truncated, conical, or other suitable form and suitable size, of brick, metal, or other material. When made of metal I prefer to construct it with double walls, *a b*, as shown in Fig. 1, in order to prevent overheating of the contents. The blast-furnace *B* is directly under the charging-vessel. *D D* are two horizontal plates, which constitute, when brought together, the bottom of the charger and the top of the furnace. The plates *D* are supported in laterally-projecting channels *d d* at the base of the charger, and have outwardly-projecting rack-bars *e e*, that gear into pinions *f f*, as shown. By turning those pinions the plates *D D* will either be moved apart to open the

bottom of the charger, or together to close the same. The shafts *g g*, which carry the pinions *f f*, are geared together so that they can only be turned at the same time, thereby insuring the simultaneous inward as well as outward movement of the plates *D D*. *E* is a hinged lid to the charger. *h* and *i* are the gas-escape pipes from the furnace. When the gates *D D* are closed together the lid *E* is opened to admit the material to be charged into the charger. The material is then properly leveled or evened within the charger and the lid then closed. The shafts *g* are then turned to draw the plates *D D* apart and allow the charge to drop into the furnace. The escape of gas through the charger is meanwhile prevented by the lid *E*. The plates *D* are subsequently closed together again, and the vessel *A* ready for another charge. Instead of the racks and pinions, levers or other equivalent devices may be used for adjusting the plates *D*.

Having thus described my invention, I claim as new and desire to secure by Letters Patent—

1. The sliding plates *D D*, arranged at the bottom of a blast-furnace charger, to move simultaneously together, or apart, as set forth.
2. The lid *E*, combined with the charger *A*, and sliding plates *D D*, substantially as and for the purpose herein shown and described.

WILLIAM A. MILES.
